UNITED STATES PATENT OFFICE.

RUSSELL S. FEICHT, OF PITTSBURG, PENNSYLVANIA, ASSIGNOR TO WESTINGHOUSE ELECTRIC & MANUFACTURING COMPANY, A CORPORATION OF PENNSYLVANIA.

DYNAMO-ELECTRIC MACHINE.

No. 926,248.

Specification of Letters Patent.

Patented June 29, 1909.

Application filed October 5, 1907. Serial No. 396,039.

To all whom it may concern:

Be it known that I, RUSSELL S. FEICHT, a citizen of the United States, and a resident of Pittsburg, in the county of Allegheny and State of Pennsylvania, have invented a new and useful Improvement in Dynamo-Electric Machines, of which the following is a specification.

My invention relates to dynamo-electric machines, and it has for its object to provide means for improving the characteristics and the operation of machines of this class in which the winding coils are disposed in open slots provided in the core members.

Induction motors and other dynamo-electric machines are often employed in places where the demands are such as to make their operation almost continuous, and when great inconvenience and loss would result if the machines should be shut down for repairs for any considerable length of time. In such cases, it is desirable to employ armatures having open slots so that injured coils may be replaced in a minimum time without disturbing the remainder of the winding.

According to my present invention, I provide an improved magnetizable wedge or strip which may be located near the top of the slots so as to obtain, as nearly as possible, the well known advantages of partially closed core slots.

Figure 1, of the accompanying drawings, is a sectional elevation of a portion of a dynamo-electric machine equipped in accordance with my invention. Figs. 2 and 3 are detail views on a larger scale of a coil wedge like those employed in the structure shown in Fig. 1. Fig. 4 is a side elevation of a portion of a coil and its magnetizable strip and Figs. 5 and 6 are sectional views taken, respectively, on lines V—V and VI—VI of Fig. 1.

Referring to the drawings, the machine illustrated comprises a laminated magnetizable core member 1 having slots 2, the sides of which lie in substantially parallel planes and provided with grooves 3 near their openings. Coils 4 are disposed in the slots in a well known manner and are held in position by wedges 5 and 6 which engage the grooves 3 and are located near the ends of the slots, as shown and described in Patent No. 765,228, granted July 19, 1904, to the Westinghouse Electric & Manufacturing Company, as assignee of Isaac De Kaiser.

Magnetizable strips 7 are located in the tops of the core slots and are bound to the straight portions of the coils between wedges 5 and 6 by insulating tape, and the ends of the strips are beveled to extend under the inner ends of the wedges. The wedges are also beveled to fit over and form splice-joints with the extremities of the strip. By binding the magnetizable strip 7 to the coil, the danger of its being displaced during the operation of the machine is avoided, and the greater part of the strain is borne by the wedges. It is necessary to insulate the strip 7 from the core as well as from the coil in order to avoid establishing local circuits through the core laminations and the strips which are located in adjacent slots. Since the magnetizable strips are located near the openings of the slots and are insulated from the core structure, it will be readily understood that the effect will be similar to that produced by partially closed slots, two air gaps being substituted for the single gap in the closed slot and the magnetizable strip taking the place of the tooth projections.

My invention is not restricted to any specific class of dynamo-electric machines, and variations in the size and arrangement of parts may be effected within the scope of my invention.

I claim as my invention:

1. In a dynamo-electric machine, the combination with a core member having a plurality of slots, and coils partially located in said slots, of magnetizable strips insulated from the coils and from the core and disposed near the openings in the slots, and insulating wrappings around the strips and the corresponding coils.

2. In a dynamo-electric machine, the combination with a core member having a plurality of open slots, coils partially located in the slots, and means for holding the coils in position, of magnetizable strips insulated from the coils and from the core and disposed in the slots outside the coils, and insulating wrappings around the strips and the corresponding coils.

3. In a dynamo-electric machine, the combination with a magnetizable core member provided with a plurality of slots each having substantially parallel sides, coils partially located in the slots, and wedges located near the ends of the slots for holding the coils in position, of insulated magnetizable strips

disposed near the openings in the slots and held in position by the wedges.

4. In a dynamo-electric machine, the combination with a magnetizable core member having a plurality of open slots, the side walls of each of which are substantially parallel, coils partially located in the slots and separated therefrom by an insulating wrapping, and a magnetizable strip insulated from each coil and secured to it by insulating wrappings and located near the opening in the slots, of wedges which extend inwardly a short distance only from the ends of the core and are adapted to hold the coils and the magnetizable strips in position.
5. In electrical apparatus, a core having teeth which form slots to receive coils and are provided with grooves in their sides, adjacent to their free ends, coils partially located in the slots and magnetizable strips secured to and insulated from the coils and disposed near the openings in the slots, of relatively

short non-magnetizable wedges the edges of which fit into said grooves.

6. In electrical apparatus, a core having teeth which form slots to receive coils and are provided with grooves in their sides, adjacent to their free ends, coils partially located in the slots, and magnetizable strips having beveled ends and secured to and insulated from the coils and located between the outer ends of the teeth, of coil-retaining wedges the edges of which fit into the grooves and the inner ends of which are beveled to form a splice joint with the outer ends of the magnetizable strips.

In testimony whereof, I have hereunto subscribed my name this 30th day of September, 1907.

RUSSELL S. FEICHT.
